UNITED STATES PATENT OFFICE.

MARY E. A. MERRITT, OF LONG BEACH, CALIFORNIA.

EASEL.

Application filed December 7, 1925. Serial No. 73,693.

This invention relates more specifically to an easel construction adapted for artists' use.

An important object of the invention is 5 to provide an easel construction that may be readily collapsed in a flat compact form when not in use for storage purposes.

Another object is to provide an easel at 10 which two artists may work at the same time without interfering with each other.

Another object is to provide a construction that may be readily assembled for use, and in which the color receptacle supporting shelves are utilized to prevent an accidental 15 collapse of the easel when in use.

A further object is to provide an easel in 20 which a plurality of sheets of drawing paper or color receiving material may be conveniently disposed and clamped to the easel working surfaces, the top or outer sheet being readily removable without disturbing the remainder.

A still further object is to provide an easel construction adapted to removably secure in 25 a convenient position a plurality of liquid color receptacles, and to provide means for receiving any drippings of color from the drawing paper during the formation of the picture or design thereon.

30 Further objects and advantages will appear from the following specification, reference being had to the accompanying drawings in which:

Fig. 1 is a perspective view of an easel constructed in accordance with the invention.

35 Fig. 2 is a front elevation of the easel.

Fig. 3 is an enlarged sectional view of the material clamping means taken on line 4—4 of Fig. 2.

40 Fig. 4 is an enlarged detail section taken on line 4—4 of Fig. 2 showing the color receptacle supporting shelf, and the drip trough.

Fig. 5 is a perspective view of an easel 45 with a single drawing board.

In an embodiment of the present invention and referring now more particularly to the double form of easel shown in Fig. 1, 5 and 6 indicate two complementary frame 50 members, consisting of two pairs of vertically disposed supporting legs 7, 8, 9 and 10, the pairs being hinged together at the top thereof in order that the frame members may be disposed at an inclination to each 55 other when the easel is in an operative position.

Secured to the front faces of each pair of the frame members, and extending downwardly and terminating midway the length of the legs are drawing boards 12, 12, rigidly 60 fastened thereto for holding the drawing material, such as paper, in convenient position for the artist.

In order to space the pair of hinged frames the proper distance apart when it is 65 desired to use the easel, each leg is provided with a longitudinally extending slot 13, adapted to receive cross braces 14, the ends of the braces extending beyond the front faces of the leg members, and each provided 70 at either end with a longitudinally extending slot 15 for receiving the ends of shelves 16 adapted to support in convenient position the liquid color receptacles used by the 75 artist in the creation of pictures.

In order to hold the frames against accidental collapse, and also to impart stability to the entire easel structure, wedge pins 17 are inserted in the oppositely disposed ends 80 of each pair of slots 15, the pins forcing the rear legs into clamped engagement with the rear longitudinally extending edges of the shelves 16, as clearly shown in Fig. 4 of the drawings.

Shelves 16 are each provided with a plurality of aligned openings 20 in which are 85 mounted the tapered receptacles 21, such as ordinary "jelly glasses", for holding the cold water paint solutions of different colors used by the artists in their work.

Each drawing board at its upper horizontal edge is provided with a clamping mechanism, adapted to hold in a fixed position on said boards a plurality of sheets 22 of drawing, or other material used by 95 artists in the production of pictures or designs, each clamping mechanism preferably consisting of a pair of threaded studs 23, secured to the drawing boards in any suitable manner, the sheets of drawing material 100 22 being suspended therefrom (see Fig. 3). In order to prevent the sheets from becoming accidentally detached from the studs a clamping board 25 is disposed on the outer ends of each pair of studs, wing nuts 26 105 forcing the boards into clamping relation with the sheets of drawing material.

These easels have been especially designed for use in connection with kindergarten schools, and as children in making colored 110 drawings usually employ an excess of liquid color some provision must be made for con-

trolling the drips falling from the sheets of drawing material, and to this end the lower horizontally disposed edge of each drawing board is provided with a trough 27 for receiving the same.

In Fig. 5 a modified form of easel construction is shown that is substantially the same as the form heretofore described, with the exception that one pair of the supporting legs is not provided with the drawing board, but in lieu of the same it is provided with a cross brace 28 located midway the length of the legs to rigidly secure the same together. The cross braces 29 are similar in form to the cross braces 14 used in the first form with the exception that one end only is provided with a slot 15 for receiving the ends of the color receptacle supporting shelves 16, as in the first form, their opposite ends being provided with apertures for the reception of wedge pins 30.

From the above description it will be apparent that I have provided a collapsible easel construction at which two children may work at the same time without interference. Further the easel may be quickly assembled when it is desired to use the same, and as quickly taken apart for storage. The shelves for holding the paint receptacles are so formed and connected to the cross braces as to lock the supporting legs in position when the easel is in an operative position. Also as the drawing boards are provided with a plurality of sheets of material utilized in painting, successive sheets may be readily detached from the pile without manipulating the clamp construction. The glass shelves or racks securely hold the color receptacles in position and as a result they are not easily upset or spilled by an accidental movement of the easel.

By providing drip trays at the base of the

drawing board all drippings from the brushes or material is prevented from dropping on the floor.

What I claim is:

1. An easel construction comprising pairs of supporting bars hingedly secured together at the top thereof, drawing boards secured to the outer face of each pair of supporting bars at the upper ends thereof, a drawing material clamping mechanism secured to the upper edge of the drawing boards, side braces detachably engaging the supporting bars, receptacle holding shelves detachably secured to the ends of the side braces for maintaining the supporting bars against movement when assembled, and horizontally extending drip troughs secured to the lower edges of the drawing boards adapted to receive excess liquid color that may drip from the material disposed on the drawing boards.

2. An easel construction comprising pairs of supporting bars hingedly secured together at the top thereof, drawing boards secured to the outer face of each pair of supporting bars at the upper ends thereof, a drawing material clamping mechanism secured to the upper edge of the drawing boards, side braces having slotted ends detachably engaging the supporting bars, transversely disposed receptacle holding shelves passing through the slotted ends of the side braces for maintaining the supporting bars against movement when assembled, and horizontally extending drip troughs secured to the lower edges of the drawing boards adapted to receive excess liquid color that may drip from the material disposed on the drawing boards.

In witness that I claim the foregoing I have hereunto subscribed my name this 21 day of November, 1925.

MARY E. A. MERRITT.
